DIRECTIVE MICROWAVE RADIO ANTENNA

George C. Southworth, Red Bank, N. J., assignor
to Bell Telephone Laboratories, Incorporated,
New York, N. Y., a corporation of New York

Original application November 28, 1941, Serial
No. 420,747. Divided and this application April
1, 1943, Serial No. 481,390

37 Claims. (Cl. 250—33.63)

1

This invention relates to the transmission of ultra-high frequency electromagnetic waves and more particularly to apparatus, systems and methods adapted for the launching of radio waves into space and for the reception of such waves. The present application is a division of my application Serial No. 420,747, filed November 28, 1941 (United States Patent No. 2,405,242, granted August 6, 1946), the disclosure of which is to be deemed incorporated herein.

The invention has as its principal object the provision of new and improved means for the directive radiation and reception of radio waves, and more especially antennas adapted for the radio beam transmission of microwaves.

One of the objects is to satisfy the need for an antenna, or unit antenna for a multiunit array, that is fairly small, generally elongated and slender, and directive principally along its axis, that is, in the direction in which it is pointed. An antenna of this kind would be especially well adapted for many applications where space, shape and weight are significant factors, as for typical example in an array or in connection with object locators or "radars" for installation on aircraft.

In an embodiment of the invention to be described in detail hereinafter, an elongated slender antenna or antenna unit with the desired "end-on" or "end-fire" characteristic is constituted of a leaky wave guide, the latter being a wave guide that is adapted to permit electromagnetic wave power guided through the interior thereof to escape substantially continuously along its length, as illustrated by an unsheathed dielectric guide operated near cut-off. In the best mode of application that I have discovered the antenna is a continuously leaky wave guide consisting essentially of a rod of dielectric material having a dielectric constant substantially greater than unity and having the characteristic that the velocity of wave propagation through the rod, i. e. the phase velocity, is substantially equal to, or slightly less than, the velocity of light in free space.

A feature of the invention is a wave reflector or quasi-piston that is adapted for longitudinal movement within a dielectric rod.

In accordance with another feature of the invention an antenna array is constituted of a multiplicity of end-fire dielectric rod antennas disposed side by side.

The invention embraces also a scanning array of stationary, differently directed end-fire antennas or the like which effectively are cyclically arrayed in groups for each direction of scanning.

2

The nature of the present invention and various objects, features and advantages in addition to those pointed out above will appear more fully from the following description of the embodiments of the invention that are illustrated in the accompanying drawings. In the drawings:

Fig. 1 illustrates an end-fire dielectric rod antenna system in accordance with the invention; Figs. 2 and 3 are curve diagrams relevant to the rod antenna of Fig. 1;

Fig. 4 illustrates an array of rod antennas; Figs. 5 to 9 show modifications of Fig. 1; and Figs. 10 to 12 illustrate radio scanning systems in accordance with the invention.

Referring more particularly now to Fig. 1, there is shown an antenna system comprising a rod 1 of solid dielectric material that is unsheathed throughout the greater part of its length and which is fitted at one end with means for exciting it with ultra-high frequency electromagnetic waves or for receiving such waves intercepted and transmitted by the rod. The phase velocity of a wave of given type or field configuration propagated through a dielectric rod is dependent on and largely fixed by the dielectric constant of the material comprising it and by its transverse dimensions, the diameter being the significant parameter in the case of a rod of circular cross section, as I have disclosed heretofore. These factors can be and are so correlated with the operating frequency that the velocity of propagation through the rod is substantially the same as the velocity c of wave propagation in free space or, more particularly, substantially the same as the velocity of propagation along the rod in the space immediately surrounding the rod.

For a particular dielectric rod made of polystyrene having a dielectric constant ϵ of 2.5 the relation between d/λ , the diameter of the rod measured in wave-lengths, and the ratio c/v_p of the velocity of propagation in free space to the velocity of propagation in the rod, takes the form illustrated graphically in Fig. 2. The dominant or H₁₁ type of dielectrically-guided wave is assumed. From the graph it will be evident that the significant ratio approaches asymptotically a value equal to the square root of the dielectric constant ϵ for increasing values of diameter and that in the other direction the ratio approaches asymptotically the desired value of unity as the diameter is progressively reduced. Experience shows that for the particular case contemplated in Fig. 2 a good range of operating diameters lies between 0.4λ and 0.5λ . In this range the velocity

of propagation is somewhat less than but within

about ten per cent of the velocity in free space. To ascertain whether the velocity of propagation for any particular dielectric rod falls within this general range one may either resort to calculations based on the general theory set forth in my U. S. Patent No. 2,129,711 or one may very simply measure the velocity by the well-known method of standing waves. In the latter case one may excite the rod at one end, place a metallic reflector at the other end and with a traveling detector or the like measure the length of the standing wave appearing along the surface of the guide. In a modification of this method the detector remains fixed and one moves the plane reflector, the latter having an aperture through which the guide extends. If this measured wavelength falls within the range noted above, conditions are appropriate for end-fire radiation.

When it is not essential that the operating frequency be of some predetermined value, it may be adjusted over a range until a frequency is found which the measuring technique described indicates to be productive of the desired velocity of transmission or which yields maximum wave intensity at some distant point on the axis. If a predetermined operating frequency be selected, then it will be necessary either to calculate the phase velocity in terms of the dimensions of the guide or progressively shave or turn down the dielectric rod until measurements indicate that the proper dimensions have been reached. Since the calculations involve troublesome transcendental equations which must be solved graphically it is often more convenient to resort to the experimental procedure. For a cylindrical polystyrene rod about 7.5 wave-lengths long, a diameter of about 0.44λ was found to be approximately correct.

Graphical solutions of the equations for different assumed values of the dielectric constant ϵ are represented in Fig. 3, where the inverse ratio v_p/c , known as the velocity constant, is plotted against d/λ on a somewhat larger scale than that employed in Fig. 2. It will be noted that in the case of polystyrene and other materials having a relatively low dielectric constant there is a comparatively wide range of values of d/λ over which the velocity constant is approximately unity, or less than unity by not more than about ten per cent. In other words, the desired velocity ratio and end-fire characteristics tend to be maintained over a comparatively wide range of operating wave-lengths, which in some instances in practice is a characteristic that is more to be desired than higher axial gain over a more limited range of wave-lengths.

Bearing in mind that the operating wave-length may be, for example, of the order of 10 centimeters or less it will be appreciated that the end-fire dielectric rod may be a slender structure especially well adapted for situations requiring a dirigible beam radiator or receiver. A structure of the proportions described could be readily mounted, for example, in an aircraft gun turret for use in object location and radio range finding and for use generally in sighting the gun and directing the aircraft under conditions of poor visibility.

The unsheathed dielectric rod, it will be understood, permits wave energy to escape throughout its length. This is especially true in the lower ranges of the transmission curve shown as Fig. 2. Where, as here prescribed, the internal and external velocities are substantially equal, the wave energy contributed by the dielectric rod to

the external field at any point is in such phase as to enhance transmission or radiation in the axial direction. The phenomenon is such, too, that for rods of moderate length the longer the dielectric rod is, the more sharply is the radiation confined to the axial direction. To at least a first approximation doubling the length of the rod in this region doubles the axial gain or sharpness of the radiation pattern.

10 Added gain may be had, too, by employing a plurality of parallel dielectric rods in array in the manner of the horn arrays disclosed in my application Serial No. 346,175, filed July 18, 1940. Such an array is illustrated in Fig. 4 although only diagrammatically. Details of the individual couplings and of the connections to the common source or receiver are omitted.

To excite the dielectric rod 1 or to take off the waves intercepted by it, means of the character illustrated in Fig. 1 may be employed. As shown, a metallic sheath 2 encloses an end portion of the rod and a metallic end cap 3 is provided. Embedded in the dielectric is a diametral conductor 4 which in one direction extends through an opening in sheath 2 as the inner conductor of a coaxial conductor tuner 5. In the other direction conductor 4 extends through the sheath as the inner conductor of a coaxial conductor line 6 which leads to the exciting source 7 or corresponding receiver. The distances from conductor 4 to end plate 3 and to the other end of sheath 2, respectively, may advantageously be so proportioned in relation to the operating wavelength as to facilitate efficient transfer of wave power between line 6 and the unsheathed or radiating portion of the rod 1. This is a matter of matching impedances and will be considered further hereinafter. To support the rod of clamp 8 is applied to the sheathed portion of the rod and attached to the top of the supporting column that is mounted on a rotatable base 9. The feed line 6 may be brought up through the supporting column or even constitute the supporting column, as illustrated.

45 Fig. 5 shows a modification of the Fig. 1 structure in which the end-fire dielectric rod 11 is of rectangular cross section. The principles underlying the design are those discussed with reference to Fig. 1 and the various parts are proportioned with the same objects in view. In one instance of practice the dielectric rod 11 consisted of a bar of polystyrene 90 centimeters long having an e dimension of 2.7 centimeters, an h dimension of 4.7 centimeters, and a measured dielectric constant of 2.5 or 2.6, the e and h dimensions being the cross-sectional dimensions that are respectively parallel and normal to the lines of electric force. The unsheathed portion of the rod was approximately 65 centimeters long and the operating frequency was 3,000 megacycles per second. The operating frequency corresponds to a free space wave-length of 10 centimeters and the indicated wave-length within the rod was approximately the same. The axial gain of the 55 structure relative to a non-directional radiator was found to be about 17 decibels. Where the combination is to be used as a receiver the transverse conductor 14, aligned with the electric field of the waves in the rod and corresponding to conductor 4 of Fig. 1, may be brought out in one direction through the sheath 12 to a tunable detector 13 of coaxial conductor type and the demodulation products taken therefrom. Good results have been obtained too with a rod of ceramic 60 material having a dielectric constant of about 30.

Fig. 5 illustrates also a new form of piston or reflector which is adapted for any type of metal sheathed wave guide and which is peculiarly adapted for a metal sheathed guide with solid dielectric. This is used in lieu of the metallic end plate 3 of Fig. 1. In a form designed particularly for dielectrically-guided waves of dominant type in a guide of rectangular cross-section the reflector comprises a set of parallel metallic baffle plates 15 disposed within the end of the metal sheathed guide section 12 and arranged to subdivide it in the h direction. Each of the subguides formed by the baffle plates has a cut-off frequency determined by the separation of the plates and the length thereof, and by proper proportioning of the parts the subguide cut-off frequency can be and is made to lie above the operating frequency, thereby blocking wave transmission. If the plates 15 are at least a wave-length long the cut-off frequency of the subguides may be readily calculated in terms of the spacing between plates. With closer spacing of the plates 15 the length thereof may be reduced without changing the cut-off frequency of the subguides. Although equations are available in published form to permit the necessary calculations to be made, it may be said that the lower limit on the spacing between plates is largely one of convenience only. The dielectric material in the end of the sheathed portion 12 is slotted to receive the plates 15 and to permit longitudinal adjustment thereof, thereby enabling ready adjustment of the point of reflection. The several plates 15 are mechanically connected by a plate 16, metallic or otherwise, and a handle 35 is attached to the assembly. The adaptation of the structure to guides of other than rectangular cross-section and to the reflection of wave types other than the dominant type will be apparent to those skilled in the art in view of the foregoing exposition of the principles involved.

Experiments have shown that in the case of the specific example described with reference to Fig. 5, metal shields placed on the outside of the unsheathed rod 11 tend to inhibit radiation but that the effect is less pronounced when partial shields are placed on the short or e sides of the radiator than it is when they are placed on the long or h sides. On the other hand, it is found that a metallic septum placed perpendicularly to the electric force and midway between the two h faces of the dielectric bar has little effect on the behavior of the radiator. This has a fortunate and a very important practical bearing for it permits the addition of metal reinforcing to a structure that might otherwise be relatively weak. Fig. 6 shows an advantageous construction embodying also other features to be described.

In Fig. 6 the dielectric rod 11 of rectangular cross-section contains an embedded metallic plate 18 which is of the same width as the rod and which is disposed parallel to and midway between the h faces thereof. At the exciter end of the rod the dielectric material is tapered down to plate 18 without change in h dimension while the plate itself flares to contact with the side walls of a hollow metal chamber 19. The latter is arranged as a wave guiding continuation of the rod 11 and is expanded in h dimension to avoid transmission cut-off. Chamber 19 includes a transverse metallic diaphragm 20 with a central slit in the h plane. In the chamber portion between diaphragm 20 and the closed left-hand end of chamber 19 means are provided for introducing

guided waves from a beating oscillator 21. In the other portion of chamber 19, at the end of metal plate 18, transverse pick-up conductor 14, connected at one end to a coaxial tuner, leads to a first detector and external coupling circuit 22 and through that to receiving apparatus not shown. The terminal apparatus illustrated is specifically adapted for receiving waves picked up by the dielectric rod, but minor modifications will make this apparatus suitable for modulation and transmission of waves. Further details will be found in my copending application Serial No. 359,643, now abandoned, filed October 10, 1940. As shown, the reinforcing plate 18 need not extend to the free end of the rod, and the portion of it within the sheath may be used as a means for attaching the radiator and terminal chamber to a supporting and orienting structure.

To prevent reflection loss the coupling at the fixed end of the end-fire dielectric rod should provide for impedance matching of the parts. In the embodiment illustrated in Fig. 7, for example, the parts comprise the unsheathed rod 11 having a certain characteristic impedance Z_1 , a metal sheathed end section 24 having a different characteristic impedance Z_2 , and a hollow-chamber-like guide portion 25 into which the tapered end of the rod extends a short distance. The chamber 25 is bounded at one end by the apertured diaphragm 26 which may separate it from a source or receiver to the left. It is a matter of experience that even if the diaphragm 26 be omitted a fairly good impedance match may be obtained merely by sliding the dielectric rod into the chamber 25 until the transmitted power is maximum. For a still better match the parts may be so proportioned that while the e dimension of the sheathed guide section 24 is the same as that of chamber section 25 the h dimension of section 25 is $\sqrt{\epsilon}$ times that of section 24. Such small discontinuity as may appear at the junction of 11 and 24 may be compensated by adjustment of the position and aperture of diaphragm 26. The tapering of the end of the rod 11 as shown makes the conditions for impedance matching less critical.

Important advantages are secured in accordance with another phase of the present invention by making the end-fire dielectric rod elastic or flexible. The dielectric rod in Fig. 7, for example, may be constructed of a material such as soft rubber so that the rod may be substantially deflected in any direction at will. Inasmuch as the direction of radiation depends on the orientation of the unsheathed rod portion, which is readily controlled by any suitable mechanical means, it is evident that this construction permits rapid radio scanning of any given section of space. Inertia may be reduced and increased flexibility in one plane derived by gradually reducing the e dimension of the rod toward the free end thereof.

For some applications flexibility in one plane only may be sufficient, and for such cases a metal mid-septum 30 may be added to the Fig. 7 structure as shown in Fig. 8. The septum not only lends support and prevents flexing in its plane but it also may be used to control the elasticity of the structure and its natural period of vibration. The latter feature may be of special utility in connection with object locators, such as aircraft spotting devices, where it is considered desirable to scan the scene cyclically with a periodicity of the order of a fraction of a second, for by properly adjusting the elasticity of the rod in relation to the mass thereof the natural period of vibration of

the flexible rod may be made to coincide more or less with the desired period of scanning. Thus, a dielectric rod of pure gum rubber having a specific gravity of 6.59 and a dielectric constant of 3.5 at 3000 megacycles, having an effective length of 61 centimeters, e and h dimensions of 2.7 and 4.8 centimeters, respectively, and a septum of brass 0.159 centimeter thick, was found to have a natural frequency of vibration of approximately 100 per minute. On substituting a septum of steel about 0.32 centimeter in thickness the resonant frequency may be increased to about 5 cycles per second. The principle of scanning applied above to a single plane may be extended to two planes by a suitable modification of the antenna structure. For example, one may use as the supporting member a relatively small metal rod of rectangular cross-section surrounded by the necessary dielectric either in circular or rectangular form. By suitably proportioning the dimensions of the core relative to its elastic properties and the mass of the surrounding dielectric, it is possible to give one period of scanning in the vertical plane and another in the horizontal plane at the same time retaining the very desirable radiation characteristics.

Fig. 9 illustrates a modification of the Fig. 1 structure adapting it for oscillatory variation of the angle of fire. The principal changes as compared with Fig. 1 are the provision of a bayonet joint 32 in the vertical coaxial feed line, thereby permitting angular adjustment of the upper end of the feed line and the transmission elements mounted thereon, and a heavy helical spring 33 connecting the stationary and movable parts. The spring is proportioned in relation to the moment of inertia of the movable parts to give the desired periodicity. The necessary power required to maintain the structure in continuous vibration may be applied through an escapement or any of a variety of mechanical devices. It will be appreciated that the coupling between the feed line and the rod, and therefore also the intensity of radiation, is not affected by the angular movement of the radiator.

For rapid scanning for higher gain and angular definition than can be achieved with a single rotating beam radiator or receiver it is of course possible to provide an array of beam antennas and to rotate the array. This may lead, however, to cumbersome structures of considerable weight and bulk not well adapted for many situations in practice. In accordance with one phase of the present invention the performance of an angularly adjustable or rotatable array is achieved with a stationary array of divergent beam antennas and a movable distributor. The latter connects the antennas, successively in groups, to the exciting source or receiver and introduces phase shift of such amount that the divergent antennas constituting the operative group at any instant cooperate to form a single beam of high intensity. Fig. 10 shows diagrammatically one form which the invention may take.

Referring to Fig. 10, a large number of stationary end-fire dielectric rods 35 are disposed radially in circular array about a central point, and a distributor or contactor 36 mounted for rotation about the central point is arranged to connect a source 37 (or receiver) to the feed ends of the dielectric rods a group at a time. By way of specific example the array may comprise thirty-six dielectric rods and the distributor may connect five at a time with the source. The distributor is of such nature that the waves supplied to the feed

ends of the connected group of rods are not in the same phase relation but differ in phase by such amount that the radiation from each rod contributes effectively to the production of a single sharp beam or, in other words, to the formation of a plane wave front $a-a$ that is normal to the central rod of the group. If the phase ϕ_0 of the waves supplied to the central rod be assigned a reference value of zero then the waves supplied to the two rods next adjoining should be advanced in relative phase by an amount ϕ_1 such that, approximately,

$$\phi_1 = \frac{2\pi r}{\lambda} (1 - \cos \theta)$$

where r is the radius of the array, λ is the wavelength in free space and θ is the angular separation between rods, which is 10 degrees in the example described. For the outer pair of rods comprising the group of five the phase advance should be

$$\phi_2 = \frac{2\pi r}{\lambda} (1 - \cos 2\theta)$$

For practical cases like that cited above ϕ_2 is approximately four times ϕ_1 . It should be understood that the principles involved do not require that the group consist of an odd number of rods, although this is considered the better arrangement.

One practical embodiment in accordance with the Fig. 10 diagram is illustrated in Fig. 11. For simplicity only a few of the dielectric rods comprising the complete array are illustrated. The distributor 36 in this case is a hollow pipe guide of rectangular cross-section comprising an arcuate portion 39 that slides along the open ends of coupling chambers 40 associated with the feed ends of the end-fire dielectric rods 35, and radial portions 41 that extend from the extremities of the arcuate portion to the central source 37. The latter comprises a coaxial conductor line which has an end portion 38 integrally connected with the distributor 36 and adapted for rotation therewith about the axis of the line. The outer vertical walls of guide sections 41, assuming the coaxial line to be vertical, extend through the outer conductor of the coaxial section 38 to tangential contact with the large inner conductor while the other walls terminate at the outer conductor. With this arrangement of parts the coaxial conductor waves supplied through the line to section 38 are translated into horizontally polarized guided waves of dominant type in the guide sections 41. Moreover, the two guided waves as thus established are in aiding phase relation in respect to the supply of wave power to the arcuate section 39. For efficient coupling, coaxial section 38 is extended above the guide portions 41 and capped with a metallic reflector, the length of the extension being critically related to the operating frequency and adjusted for maximum radiation.

The arcuate portion 39 of the distributor has in its outer vertical face a plurality of apertures, represented as vertical slots 42, one for each of the rods comprising the group, and having the same angular separation. Through the slots 42 wave power is communicated to the coupling chambers 40, the open ends of which are otherwise completely closed by the outer face of the distributor. The chambers 40 may be as illustrated in Figs. 7 and 8 but flared as shown so that they are contiguous at the outer face of the distributor, so that as the distributor rotates wave

power is continuously supplied to one or another group of five. Preferably the arcuate passage 39 is tapered in *e* dimension from a maximum at its extremities to a minimum at its center whereby impedance matching with the radial portions 41 is facilitated.

It is to be noted that the waves supplied through the radial branches 41 reach first the outer pair of rods 35 and that the phase here is advanced relative to the phase at the central rod by an amount corresponding to the time of wave transmission from the outermost slots 42 to the central slot. Similarly there is a phase advance at the inner pair of slots relative to the central slot. If necessary, phasing loops 43 may be interposed between slots in the arcuate-guide portion 39 whereby the electrical distance and phase displacement between slots can be adjusted as desired. By suitable proportioning of the parts these phase differences may be made to coincide with the desired values of ϕ_1 and ϕ_2 hereinbefore indicated.

Another embodiment in accordance with Fig. 10 is illustrated in Fig. 12. Only the distributor and source are shown, for the coupling chambers and dielectric rods may be the same as in Fig. 11. In this case the vertical feed guide consists of a cylindrical metal pipe guide with a rotatable end portion 44 terminated by an end reflector. Waves of symmetric magnetic or H_{01} type are supplied through the guide to a plurality of longitudinal slots 45 spaced apart circumferentially in the wall of guide section 44. Integrally connected to section 44 are five contiguous flaring pipe guides 46 of rectangular cross-section which are disposed over respective slots 45 and supplied with wave power therethrough. At their other ends the guides 46 are covered by an arcuate metal plate adapted to ride against the exposed ends of the coupling chambers 40, and vertical slots 42 are provided as before for escape of wave power into the coupling chambers from the respectively associated guides 46. The required relative phase displacements ϕ_1 and ϕ_2 are obtained by phase shifters 47 disposed in the two outer pairs of radial guides. The phase shifters may be of any suitable type, such as a pair of iris diaphragms or other reactors critically spaced apart in relation to the operating wave-length and the phase shift desired.

What is claimed is:

1. An antenna system comprising as the wave radiating or intercepting element a rod of dielectric material having a dielectric constant substantially greater than unity, and means at one end of said rod for launching into said rod or for receiving therefrom only electromagnetic waves of a predetermined operating frequency, the transmission cut-off frequency of said rod being not substantially greater than the said operating frequency, the length of said rod being at least several wave-length at the operating frequency.

2. As a radio antenna, a leaky wave guide having a transmission cut-off frequency that substantially coincides with the operating wave frequency.

3. A microwave radio system comprising as a wave radiating or radio wave intercepting element thereof a continuously leaky wave guide, and non-radiating wave translating means coupled to said guide for exciting therein electromagnetic waves of a predetermined frequency adapted for guided propagation therethrough with leakage of wave energy therefrom into free

space continuously along said guide or for receiving from said guide such waves propagated therethrough and excited therein by radio waves incident thereon.

5. In a microwave radio system, a radio antenna comprising a continuously leaky electromagnetic wave guide, said guide being terminated at one end in free space, a conductively shielded non-radiating transmission line coupled to the other end of said guide in substantially impedance matching relation therewith, and wave translating means including said line for exciting in said guide electromagnetic waves of a predetermined frequency and field configuration for guided propagation therethrough toward said one end with radiation of wave energy continuously along said guide, or for receiving from said guide such waves propagated therethrough toward said other end and excited therein by radio waves incident thereon.

10. A microwave radio system comprising a leaky wave guide as a wave radiating or radio wave intercepting element thereof, said guide having a free end terminating in space, and wave translating means coupled to said guide at a distance from said free end for applying ultra-high frequency electromagnetic waves to said guide for propagation therethrough toward said free end with continual radiation therefrom or for receiving from said guide such waves excited therein by radio waves intercepted by said guide, said translating means being itself non-radiating, and said guide being transversely dimensioned to guide the travel of the waves being propagated in said guide with a phase velocity substantially equal to that of light in free space.

15. A microwave radio system comprising as a wave radiating or intercepting element thereof a leaky wave guide the transmission cut-off frequency of which substantially coincides with the operating wave frequency, said guide being terminated at one end in free space, and wave exciting or receiving means coupled to said guide at a point a plurality of wavelengths removed from said one end for exciting within said guide the waves to be radiated or for receiving therefrom waves excited therewithin by incident radio waves.

20. A microwave radio system comprising as the antenna a continuously leaky wave guide which is dimensioned to have at all operating wave frequencies a velocity constant that is less than but within about 10 per cent of unity, and wave translating means at one end only of said guide for exciting said guide with the waves to be radiated or for receiving radio waves intercepted by said guide, said translating means being configured for selective translation of non-circularly symmetric guided waves in said guide, and said system being further characterized by an end-fire radiation pattern.

25. An antenna for ultra-high frequency radio waves comprising an unsheathed dielectric rod having a dielectric constant substantially greater than unity, said rod being so dimensioned that the velocity of wave propagation therethrough at the operating wave frequency is approximately equal to the velocity of electromagnetic waves in free space.

30. A microwave radio system comprising an elongated, slender antenna having an end-fire characteristic, said antenna consisting of a leaky wave guide, and guided wave exciting or receiving means coupled to said guide at only one point thereof for exciting waves in said guide for radi-

ation therefrom or for receiving therefrom waves excited therein by incident radio waves.

10. As a radio antenna, a leaky wave guide comprising an unsheathed rod of dielectric material having a dielectric constant substantially greater than unity, said guide having a transmission cut-off frequency that is at least approximately the same as the frequency of the waves being radiated or received.

11. In a microwave radio system, an antenna comprising a continuously leaky wave guide, said guide being transversely dimensioned to have a phase constant substantially equal to that of free space over a predetermined wave frequency range, and wave translating means for operating said antenna only at frequencies within said frequency range.

12. As a radio antenna, a rod of low-loss dielectric material having a dielectric constant of about two and one-half at the operating wave frequency, said rod being of substantially circular cross-section and having a diameter of from four-tenths to one-half wave-length at the operating wave frequency.

13. As a radio antenna, a rod of dielectric material having a dielectric constant substantially greater than unity, said rod being of circular cross-section and having a diameter such that its phase constant is substantially unity at the operating wave frequency.

14. As a radio antenna, a rod of dielectric material having a dielectric constant substantially greater than unity, said rod having transverse dimensions such that the transmission cut-off frequency of said rod is substantially equal to the operating wave frequency.

15. As a radio antenna, a rod of dielectric material having a dielectric constant substantially greater than unity, said rod being of circular cross-section and having a diameter such that the transmission cut-off frequency of said rod is substantially equal to the operating wave frequency.

16. As a radio antenna, a rod of dielectric material having a dielectric constant substantially greater than unity, said rod being transversely dimensioned to guide the travel of waves therethrough with a phase velocity that is substantially equal to that of light in free space at the operating wave frequency.

17. A microwave radio system in which the antenna comprises a rod of dielectric material having a dielectric constant substantially greater than unity, means for exciting electromagnetic waves of predetermined frequency and of dominant type in said rod for propagation therethrough and radiation laterally therefrom or for receiving such waves intercepted by said rod and propagated therethrough, said rod being transversely dimensioned to guide the said waves propagated through said rod with a phase velocity so closely approximating that of light in free space that said rod exhibits an end-fire directional characteristic with respect to the said waves.

18. A microwave radio system comprising as a wave radiating or intercepting element thereof a rod of dielectric material having a dielectric constant substantially greater than unity, and electromagnetic wave translating means coupled to said rod for launching waves into said rod for propagation therethrough with substantial escape of wave energy laterally therefrom into space, or for receiving from said rod waves

propagated therethrough and excited therein by intercepted radio waves.

19. A microwave radio system comprising as a wave radiating or intercepting element thereof a rod of dielectric material having a dielectric constant substantially greater than unity, the length of said rod being at least several wave-lengths at the operating wave frequency, and electromagnetic wave translating means coupled to one end only of said rod, said translating means constituting means for launching waves into said rod for propagation therethrough with substantial radiation of wave energy laterally therefrom into space, or for receiving from said rod waves propagated therethrough and excited therein by intercepted radio waves.

20. In a microwave radio system, an antenna comprising a rod of dielectric material having a dielectric constant that is at least double that of air, an ultra-high frequency wave transceiver, and means coupling said transceiver to said rod adjacent one end thereof for exciting waves in said rod for propagation therethrough toward the other end thereof with continual radiation therefrom or for receiving waves propagated in the opposite direction through said rod and excited therein by intercepted radio waves, and means for preventing substantial translation of wave energy between said transceiver and space excepting as said translation takes place through said rod, said other end of said rod terminating in space.

21. A combination in accordance with claim 20 in which said last-mentioned means comprises means conductively shielding said coupling means to provide a substantially non-radiating connection between said rod and said transceiver.

22. As a radio antenna, a rod of dielectric material having a dielectric constant substantially greater than unity, said rod being transversely dimensioned to guide electromagnetic waves of the operating wave frequency through the interior of said rod with a phase velocity that is, throughout the length of said rod, less than but within about ten per cent of the velocity of light in free space.

23. As a radio antenna, a rod of dielectric material having a dielectric constant substantially greater than unity, said rod being transversely dimensioned to guide electromagnetic waves of the operating wave frequency through the interior of said rod with a phase velocity that is substantially equal to that of light in free space.

24. In a microwave radio system, an antenna comprising an unsheathed rod of dielectric material, and means for establishing in said rod or receiving therefrom dielectrically guided waves of dominant type, said rod being dimensioned to guide said waves through the interior of said rod with a phase velocity that is substantially equal to the phase velocity of electromagnetic waves in space externally of the rod, whereby said rod has an end-fire characteristic.

25. A system in accordance with claim 18 in which said rod is of substantially rectangular cross-section.

26. A system in accordance with claim 18 in which said rod is tapered.

27. An antenna array comprising a multiplicity of unit antennas in accordance with claim 9 disposed side by side.

28. An antenna array comprising a multiplicity of like directed unit antennas in accordance with claim 1.

29. A radio antenna in accordance with claim 2 comprising an elastically flexible leaky wave guide, and means for flexing said guide.

30. A structure in accordance with claim 18, said rod of dielectric material having the electrical and mechanical properties of gum rubber.

31. A structure in accordance with claim 18 including a strengthening member extending length-wise through the rod.

32. A structure in accordance with claim 18, said leaky wave guide comprising a flexible rod of dielectric material and a stiffening member extending lengthwise of the rod.

33. A structure in accordance with claim 18 including a metallic stiffening member contiguous with said material and extending along the length of said rod, said rod and stiffener being so proportioned that the velocity of propagation of waves transmitted therethrough is at least approximately equal to the velocity of said waves in free space.

34. A structure in accordance with claim 33 in which said stiffener is a flat strip embedded within the said dielectric rod and disposed with its plane normal to the electric vector of said waves.

35. A dielectric rod for the transmission of microwaves, coupling means for exciting said rod or receiving waves therefrom, said rod being conductively sheathed for a portion of its length comparable with the length of said waves, said coupling means being embedded wholly within said sheathed portion and positioned therein for maximum coupling with the unsheathed portion of said rod.

36. A microwave radio antenna system comprising a rod of a dielectric material that has a

dielectric constant substantially greater than that of air, said rod having a conductively unsheathed portion that is a plurality of wavelengths long at the operating wave frequency and a conductively sheathed portion contiguous to said unsheathed portion, said sheathed and unsheathed portions differing in characteristic impedance, said sheathed portion having a reflecting termination at the end thereof remote from said unsheathed portion, and wave translating means coupled to said sheathed portion at a point spaced from said remote end for exciting waves to be propagated in and radiated from said unsheathed portion or for receiving waves intercepted by and propagated in said unsheathed portion.

37. A system in accordance with claim 36 in which the length of said sheathed portion and the spacing of said coupling point from the said remote end are correlated for maximum coupling between said translating means and said unsheathed portion of said rod.

GEORGE C. SOUTHWORTH.
